UNITED STATES PATENT OFFICE

126,639

DESIGN FOR A CASING FOR SOUND APPARATUS

David C. Rockola, Chicago, Ill., assignor to Rock-Ola Manufacturing Corporation, Chicago, Ill., a corporation of Delaware

Application February 5, 1941, Serial No. 98,750

Term of patent 3½ years

To all whom it may concern:

Be it known that I, David C. Rockola, a citizen of the United States, residing at Chicago, in the county of Cook and State of Illinois, have invented a new, original, and ornamental Design for a Casing for Sound Apparatus, of which the following is a specification, reference being had to the accompanying drawing, forming a part thereof.

Fig. 1 is a perspective view of a casing for

sound apparatus showing my new design, the two side walls of the casing not shown in said figure being similar to the side wall shown at the left in the perspective; and

Fig. 2 is a top plan view of the casing shown in Fig. 1.

I claim:

The ornamental design for a casing for sound apparatus, substantially as shown and described.

DAVID C. ROCKOLA.
